MATERIAL HANDLING TRAILER

Jack E. Moll, New Berlin, Wis., assignor to Miller Tilt-
Top Trailer, Inc., Milwaukee, Wis., a corporation of Wisconsin

Filed July 29, 1965, Ser. No. 86,350

Term of patent 14 years

(Cl. D14—3)

FIG. 1 is a perspective view of the material handling trailer.

FIG. 2 is a perspective view of the trailer shown in FIG. 1 taken from the opposite side.

The portion of the trailer shown in broken lines is included for illustrative purposes only.

I claim:

The ornamental design for a material handling trailer, substantially as shown and described.
